UNITED STATES PATENT OFFICE.

MAX HOGE, OF CHICAGO, ILLINOIS, ASSIGNOR TO SEFTON MANUFACTURING CORPORATION, OF CHICAGO, ILLINOIS, A CORPORATION OF NEW YORK.

DISPLAY BOX.

Application filed March 23, 1922. Serial No. 545,947.

This invention relates to improvements in display boxes and its purpose is to provide improved means for supporting a box in an inclined position. Although the invention 5 may be employed in connection with various forms of boxes, it is particularly applicable to folding boxes constructed of paper, cardboard or the like. The principal object of the invention is to provide a box 10 having an improved easel attachment for supporting it in an inclined position. A further object is to provide a folding box formed from a one-piece blank comprising parts adapted to form an easel when the box 15 is assembled. Still another object is to provide a folding box including an easel attachment which may be readily assembled or disassembled and arranged to occupy a small space when packed for shipment.

20 These and other objects will appear more clearly from the following specification taken with the accompanying drawing in which one embodiment is illustrated. In the drawings:

25 Fig. 1 shows a plan view of a paper or cardboard blank comprising all of the parts which make up the assembled box;

30 Fig. 2 is a perspective view showing the box in a folded or collapsed position adapted to be packed for shipment;

35 Fig. 3 is a perspective view of the partially assembled box showing the cover in open position and the parts of the easel partially assembled;

40 Fig. 4 is a perspective view of the completely assembled box showing the easel folded beneath the bottom of the box; and

45 Fig. 5 is a perspective view showing the use of the box for display purposes with the cover in open position and the easel supporting the box in an inclined position.

In the accompanying drawings the complete box is shown as being formed from a paper or cardboard blank 10 which comprises 50 in one integral piece all of the parts of the box. Describing these parts by reference to the positions which they occupy when the box is assembled, the blank comprises a bottom wall 11 which is united to its forward end along a crease or fold line 12 with the front wall 13. The bottom wall is united at its opposite edge along a parallel crease or fold line 14 with a rear flap 15. This flap 55 is united along a parallel fold line 16

with the cover 17. The bottom wall 11 is 60 united at its ends along fold lines 18, extending at right angles to the fold lines 12 and 14, with end flaps 19 which have substantially the same dimensions as the front wall 13 and the rear flap 15. The front wall 13 is 65 united at one end along a fold line 20 with an end wall 21 and this end wall has a triangular shaped flange 22 projecting from the lower edge thereof adjacent one end. The other end of the front wall 13 is united 70 along a fold line or crease 23, extending parallel to the fold line 20, with the other end wall 24 which is provided with a triangular shaped flange 25 extending from the lower edge thereof in a position similar to that 75 occupied by the flange 22 on the end wall 21. The end wall 24 is united at the end thereof opposite the front wall 13, along a crease or fold line 27, with the rear wall 28 and this rear wall is united at its opposite 80 end, along a fold line 29, with a tab 30 which is adapted to be secured by glue or other fastening means to the outer extremity of the end wall 21. A cover supporting 85 flap 31 is united to the top edge of the rear wall 28 along a fold line 32 and the opposite edge of the rear wall is united along a fold line 33 with an easel extension 34. The opposite ends of the extension 34 are united along fold lines 35 with the extension flaps 36 which are cut away on their upper sides 90 to form V-shaped notches having inclined edges 37 and 38, thus forming projecting tongues 39 at the outer corners of the extension flaps. The blank may also comprise a front flap 40 which is united to the top edge 95 of the front wall 13 along the fold line 41. The ends of the front flap 40 are united along fold lines 42 with small ears 43 located adjacent the outer edge of the flap 40 and adapted to hold other parts of the box in assembled relation, as hereinafter described. A flap may also be formed on the front edge of the cover to extend downwardly into the box parallel to the front wall 100 when the parts are assembled.

In assembling the blank into the arrangement illustrated in Fig. 2 in which it may be conveniently packed for shipment or from which it may be unfolded into the form of a 105 box, the end flaps 19 are first folded over on the fold lines 18 until they occupy positions parallel to and in contact with the

upper surfaces of the bottom wall 11. The rear flap 15 and the cover 17 are then folded about the line 14 until they overlie the end flaps 19 in positions parallel to the bottom wall. The end wall 24 and the rear wall 28 with the parts carried thereby are then folded about the line or crease 23 until they occupy positions parallel to the front wall 31 and the end wall 21. One extension flap 36 will then be inclined to the bottom wall of the box and the edges of these flaps together with the lower edge of the easel extension will serve in conjunction with the forward edge of the box along the fold line 12 to support the box in the inclined position shown in Fig. 5. When in this position, adapted for display purposes, the cover 17 is supported in an upper inclined position by the cover supporting flap 31 formed on the upper edge of the rear wall 28, it being understood that the connection between the rear wall and the flap 31 has sufficient stiffness to allow the flap 31 to maintain an upper inclined position when supporting the weight of the cover. Suitable advertising material may be printed on the inside of the cover 17 to advertise the contents of the box when it is supported in this display position.

When it is desired to store or ship the box while it is filled with goods, the cover 17 and the cover supporting flange 41 may be folded downwardly until they occupy the positions illustrated in Fig. 4, and the easel may be caused to occupy a position parallel to the bottom of the box by folding the flanges 22 and 25 into positions parallel to the bottom 11 and then folding the easel extension 34 into a similar parallel position with the easel extensions 36 lying in contact therewith and between the part 34 and the bottom of the box, as illustrated in Fig. 4.

Although a particular embodiment of the invention has been shown and described for purposes of illustration, it will be understood that it may be constructed in various other forms without departing from the scope of the appended claims.

I claim:

1. The combination in a box of a rear wall, an easel extension attached to the lower edge of said rear wall, an extension flap attached to said easel extension and extending forwardly therefrom, an end wall comprising two parallel members, one of which is continuous with said rear wall, and a projection formed on said extension flap and adapted to extend upwardly between the parallel members of said end wall.
2. The combination in a box of a rear wall, an end wall continuous with said rear wall, an easel extension attached to the lower edge of said rear wall, a front wall connected to said end wall, a bottom wall connected to said front wall, an extension flap extending forwardly from said easel extension, and a projection formed on said extension flap to extend upwardly between said bottom wall and said end wall.
3. The combination in a box of a rear wall, an end wall continuous with said rear wall,

- an easel extension attached to the lower edge of said rear wall, a front wall connected to said end wall, a bottom wall connected to said front wall, an extension flap extending forwardly from said easel extension, and a projection formed on said extension flap to extend upwardly between said bottom wall and said end wall, said end wall having an integral extension projecting downwardly on the side of said extension flap opposite the side of said projection which is engaged by said end wall. 5 60
10. The combination in a box of a rear wall, an end wall attached at one end to said rear wall, a front wall attached at one end to said end wall, a bottom wall attached to the lower edge of said front wall, an end flap attached to said bottom wall and adapted to extend upwardly beside said end wall, an easel extension formed on the lower edge of said rear wall and having a part extending forwardly with the lower edge thereof inclined to said bottom wall, and a projection formed on the forwardly extending part of said easel extension to extend upwardly between said end wall and said end flap. 15 65
15. The combination with a box comprising a rear wall and an end wall of an easel extension extending downwardly from said rear wall, and an extension flap extending forwardly from said easel extension and having a part projecting upwardly on the inner side of said end wall, said end wall having a part extending downwardly a substantial distance on one side of said extension flap. 20 70
20. The combination in a box comprising a cover, a rear wall and an end wall, said two latter walls being united at their ends, of an easel extension extending downwardly from said rear wall, an extension flap extending forwardly from said easel extension parallel to said end wall, said extension flap having an upper edge inclined to its lower edge and means carried by said end wall for holding said upper edge substantially in alignment with the lower edge of said end wall. 25 75
25. The combination in a box having a rear wall and an end wall of an easel extension extending downwardly from said rear wall, said easel extension having a flap extending forwardly parallel to said end wall, said flap having its upper side cut away to form a projection adjacent the end thereof opposite said rear wall and to form an edge inclined to its lower edge, said projection being adapted to extend upwardly on one side of said end wall, said end wall having a part adapted to extend downwardly below said inclined surface on the side of said flap opposite that on which said end wall engages said projection. 30 80
30. A folding box comprising a front wall, end walls and a rear wall continuous therewith and united with said front wall to form an enclosure, another rear wall, a bottom wall and a cover united to one edge of said latter rear wall, and an easel extension united to said first rear wall. 35 85
35. A box comprising a plurality of connected folding exterior wall members adapted to form an enclosure, a bottom wall united along one edge to the lower edge of one of said wall members, an easel extension united along one edge to the lower edge of another of said wall members, a cover united to still another one of said wall members, and a cover supporting flap united to the top edge of the wall member to which said easel extension is united. 40 90
40. A folding box comprising four lateral exterior walls adapted to form a rectangular enclosure, a bottom wall united to one longitudinal edge of one of said lateral walls, a flap united to the opposite edge of said bottom wall, a cover united to said flap, and an easel extension united to a lateral wall opposite the said wall to which said bottom wall is united. 45 95
45. A folding box comprising four lateral exterior walls united along fold lines to form a rectangular enclosure, a bottom wall united along a fold line to one longitudinal edge of one of said lateral walls, a flap united along a fold line with the opposite edge of said bottom wall, a cover united along a fold line with the edge of said flap opposite said bottom wall, end flaps united along fold lines with the ends of said bottom wall, and an easel extension united along a fold line with a lateral wall opposite the said wall to which said bottom wall is united. 50 100
50. The combination with a box, a rear wall, and end walls comprising two members, said rear wall having an easel continuous therewith and formed with a projection, one of said end members having a downwardly extending portion adapted to substantially overlie the inner face of said easel when the projection of the easel is in engagement between the members of said end wall. 55 105
55. A box having a bottom, a rear wall comprising two members one of which is continuous with said bottom and the other of which is continuous with an end wall, said latter member having a flap for supporting a cover, and an easel continuous with the bottom edge of said latter member. 60 110

MAX HOGE.
